CAR TRUCK BRAKE.

No. 403,298.

Patented May 14, 1889.

UNITED STATES PATENT OFFICE.

JOHN STEPHENSON, OF NEW YORK, N. Y.

CAR-TRUCK BRAKE.

SPECIFICATION forming part of Letters Patent No. 403,298, dated May 14, 1889.

Application filed July 20, 1888. Serial No. 280,509. (No model.)

To all whom it may concern:

Be it known that I, JOHN STEPHENSON, a citizen of the United States, residing at New York, in the county and State of New York, 5 have invented certain new and useful Improvements in Car-Truck-Wheel Brakes, of which the following is a full, clear, and exact specification.

Tram-cars usually have their wheel-brake 10 shoes pendent to the car-body and above the plane of the springs. This, although best as cars are ordinarily constructed, has disadvantages, because as the wheel center and circumference remain always equidistant above 15 the rails the contacting sole of the shoe is subject to change as the vertical motion of the car-body varies with its changeable load; therefore it becomes necessary to remove the inactive shoe remote from the wheel to prevent 20 undesirable contact of wheel and shoe. In order to obviate these objections I construct and arrange the parts as will be hereinafter fully described, and as illustrated in the accompanying drawings, in which—

25 Figure 1 is a plan of a car-truck and attachments illustrating my improvements. Fig. 2 is a sectional elevation on the line 2 2, Fig. 1. Fig. 3 is a detached section on the line 3 3, Fig. 1. Fig. 4 is an edge view of one of the 30 wheels, showing the box-sill and support for the latter. Fig. 5 is a detached view showing the connection between the brake-shoe and its operating-bar.

35 A tram or cable car with the truck-frame suspended by the axle-box shells, as this, has among its advantages the possibility of using a wheel-brake that is free from detriments referred to and possessing more power, quickness, readiness of adjustment, durability, and 40 facility for repairs.

The truck-frame is carried by its sills 5 5, attached to pendants 4, integral to the axle-box shells 3, as shown in Fig. 4, and these sills are the chief supports of the mechanism 45 of the wheel-brake, as also of the track-brake, (not shown,) which is housed immediately under the wheel-brake. Assuming that a proper car-truck exists, the following is a satisfactory method of constructing my improved 50 car-wheel brake: The wheel-brake shoe 30 may be of usual form with eye 31 and socket adapted to receive the hook with its shoulders embedded to be flush with the side face of the shoe. The shoe-sliding bar 33 has at

its head a hook, 50, with peculiar shoulders 55 adapted to be indented into the shoe-back flush with the side face of the brake-shoe and the hook fitted for passing beyond the shoulder-sockets and through the remaining thickness of the shoe and beyond the shoe 60 sufficiently to receive a vertical pin or key, 51, or other known safety-lock.

The shoe-sliding bars carry each one shoe located at the head of the bar, and at a short distance from the shoe the bar rests on a 65 cross-timber, 9, of the truck, permitting free end motion through a box-guide, 34, and another keeper, 35, secured to the truck-sill guides the tail of the shoe-bar. Each shoe-sliding bar has near its head a lug, 36, receiving one end of an extensible bar, 38, adjustable in length by a turn-buckle, 32, and the other end of the bar is jointed to an arm of a rock-shaft, 37. On the opposite side of the rock-shaft is a second arm connected with an 70 other extensible bar, lug, shoe-bar, and shoe. A third arm, 39, on the rock-shaft holds the end of a connecting-rod, 40, with its farther end jointed to one of three arms, 41 42 43, 75 on a rock-shaft, 44, attached beneath the car-floor. One arm, 42, on this floor rock-shaft has a rod, 45, connected with a lever or handle, 46, adapted to transmit the energy of the operator through the handle, rod, shaft 44, parallel rods, truck rock-shafts, bars 32, lug-shoe 80 bars, and shoes to the car-wheels at one side of the car, and for the other side a similar combination of mechanism is actuated from the third arm, 43, of the floor rock-shaft, 85 through a second parallel rod, 40, which connects with an arm of the truck rock-shaft and its connection with the brake-shoes at that side, thus completing the two sides of the 90 brake system adapted to transmit the energy of the operator to the four wheels of the two 95 sides of the car. To secure the recoil of the brake, the third arm, 39, of each truck rock-shaft has connection with the end of a recoil-rod, 48, on which is a series of spiral springs, 49, with one end of the spring abutting a shoulder or enlargement of the rod-guide through which the rod travels back and forth. Thus, when brakes are applied, the springs are compressed, and when the operator ceases his energy the springs recoil and the brake mechanism is readjusted and the shoes removed 100 from the wheels.

The following elements are included in the

combination forming the substantially-complete mechanism of the brake in addition to the car-truck and to the car-bottom, which holds the floor rock-shaft and the operator's lever or handle; four brake-shoes, four shoe-bars, eight shoe-bar guides, four articulated adjustable (connecting) bars, two truck rock-shafts, one floor rock-shaft, two recoil-rods with springs adjustable, two parallel rods connecting floor and truck rock-shaft, one operator's lever or handle, and one operator's connecting-rod.

I do not here claim the construction of the truck-frame, as the same constitutes the subject of a separate application for Letters Patent, Serial No. 280,508.

I claim—

1. A car-wheel brake with four shoes constructed to be slipped sidewise on four tenons of four slide-bars, supported by four cross-rails of a truck, with four wheels on two axles, having four journals outside of the four wheels, with four axle-boxes having four pendent limbs, to which are connected the four corners of the car-truck, substantially as and for the purpose described.

2. A car-brake shoe having a lug at one side of the center of the back, provided with a polygonal mortise and adapted to fit a laterally-extended polygonal tenon at the end of the brake-shoe bar, and having a fastening device to retain the shoe in an invariable vertical position, substantially as described.

3. A wheel-brake shoe with a transverse mortise or eye in part of its thickness, and a recess in the remaining part of its thickness, the mortise and recess adapted to the tenon and shoulder of a brake-shoe bar to hold the shoe perpendicular in its movements to and from the car-wheel, substantially as and for the purpose described.

4. A wheel-brake-shoe bar with part of its head forming a shoulder against which the brake-shoe rests, and another part extended to form a tenon adapted to occupy a correspondingly-shaped mortise in the brake-shoe, whereby the combination of the shoulder with the tenon is adapted to maintain the brake-shoe in a vertical position when moved to and from the car-wheel, substantially as described.

5. A car-wheel brake having a slide shoe-bar, with a lug fitted to receive the end of an extensible bar connected with an arm of the truck rock-shaft, substantially as and for the purpose described.

6. A car-wheel-brake-shoe bar resting on a section of a cross-bar between the wheel-faces, and carrying a shoe at the head of the bar, with the tail of the bar free to slide through a keeper secured to the inner side of the truck-sill, substantially as and for the purpose described.

7. A car-wheel brake with its shoe-sliding bar in a guide-box on the truck cross-rail and the end of said bar in a guide secured to the

truck-sill, substantially as and for the purpose described.

8. A car-wheel-brake rock-shaft with ends journaled to the sills and sub-sills sustained below the axles and pedestals by pendants integral with the axle-box shells, each rock-shaft having an arm with articulated rod adapted to transmit the energy of the operator to the brake mechanism, substantially as and for the purpose described.

9. A car-truck with its four corners carried by four integral pendants of four axle-boxes on four journals of two axles having on them four wheels, the sills and sub-sills of the truck sustaining the bearings of four journals of two rock-shafts, with their arms and connecting-rods adapted to communicate the energy of the operator to move the four brake-shoes to and from the four car-wheels of the truck, substantially as shown and described.

10. A car-wheel brake having at each side of the car-truck an arm on opposite sides of a rock-shaft, each arm having an articulated bar capable of expansion and contraction lengthwise between the arm and the lug of the sliding shoe-bar, which, with its shoe, is borne by a cross-rail of the truck, substantially as and for the purpose described.

11. A car-wheel-brake mechanism carried by a truck borne by its four corners beneath four pendants integral to four axle-box shells on four axle-journals of two car-axles with four wheels, the two truck rock-shafts having four arms connected by four articulated adjustable rods with four lugs on four sliding bars resting on four cross-bars of the truck and carrying four brake-shoes adapted to be moved horizontally to and from the wheels by the energy of the operator transmitted through a floor rock-shaft secured to the car-body beneath its floor, and an arm on each end of the floor rock-shaft having rod-connections with the rock-shaft at each side of the truck, substantially as and for the purpose described.

12. A wheel-brake rock-shaft arm holding a recoil-rod on which is a spring adapted to retract the brake, substantially as and for the purpose described.

13. A car-wheel-brake mechanism composed of brake-shoes, shoe-bars supporting the same, guides for said bars, articulated bars directly or indirectly connecting the shoes to the rock-shafts, recoil-rods connected to retract the brake, parallel rods connecting the floor and truck rock-shafts, and an operator's lever-handle connected with the rock-shaft by an operator's energy-transmitting rod, all arranged to operate substantially as and for the purpose described.

In testimony whereof I have signed my name to this specification in the presence of two subscribing witnesses.

JOHN STEPHENSON.
